UNITED STATES PATENT OFFICE.

JOHN H. ADAMS, OF MINNEAPOLIS, MINNESOTA.

PAPER-FOLDING MACHINE.

Application filed September 27, 1926. Serial No. 137,962.

My present invention relates to paper folding machines, but is especially adapted for use in folding letters, invoices, statements, advertising matter and the like shaped to be placed within envelopes.

To the above end, generally stated, the invention consists of the novel devices and combinations of devices hereinafter described and defined in the claims.

10 Said invention has for its object to provide an extremely simple, noiseless and highly efficient machine that is positive in its action and accurate as to the work done while at the same time it has a capacity for rapidly turning out work.

In the accompanying drawings, which illustrate the invention, like characters indicate like parts throughout the several views.

15 Referring to the drawings:

20 Fig. 1 is a plan view of the paper-folding machine;

Fig. 2 is a view principally in right side elevation with some parts broken away and other parts sectioned;

25 Fig. 3 is a fragmentary view with some parts sectioned on the line 3-3 of Fig. 2, on an enlarged scale, with the sheet shown in a different position by means of broken lines;

30 Fig. 4 is a fragmentary view principally in central vertical section taken on the line 4-4 of Fig. 1, on an enlarged scale;

Fig. 5 is a detail view principally in section taken on the line 5-5 of Fig. 1, on an enlarged scale;

Fig. 6 is a view corresponding to Fig. 5 with the exception that the machine is adjusted for a different folding action;

40 Fig. 7 is a view partly in elevation and partly in transverse vertical section taken on the line 7-7 of Fig. 6;

Fig. 8 is a plan view of the folding plate and a sheet folded thereon, removed from the machine;

45 Figs. 9 to 12, inclusive, are detail views principally in transverse vertical section on the lines 9-9, 10-10, 11-11 and 12-12 of Fig. 3;

Fig. 13 is a fragmentary detail view 50 principally in front end elevation with some parts sectioned on the line 13-13 of Fig. 4;

Fig. 14 is a detail view principally in longitudinal section taken on the irregular line 14-14 of Fig. 12; and

55 Fig. 15 is a perspective view of a sheet as

it will appear when folded longitudinally by the machine, and having indicated thereon, by means of broken lines, where the sheet will be folded transversely by the machine.

The numeral 16 indicates the skeleton 60 frame of the paper folding machine, on the top and forward portion of which is a flat horizontal table 17 for supporting a stack of letter sheets or similar sheets α to be folded. Front and rear co-operating combined 65 feeding and longitudinal folding rollers 18 and 19, respectively, extend transversely of the machine and have their shafts journaled in the side bars of the frame 16. The front roller 18 is located at the rear end of the 70 table 17 with its upper surface substantially in the plane of the top of said table. The rear roller 19 has a diameter slightly less than that of the front roller 18 and its axis is located slightly below that of said 75 roller 18.

A pair of laterally spaced hanger bars 20 have their upper ends rigidly secured to the top cross bar of the frame 16. The driven shaft 21 of a relatively small roller 22 is 80 journaled in the hanger bars 20 at the lower end portions thereof and has keyed to one of its ends, outward of the respective hanger bar 20, a large wheel 23. This wheel 23 is driven from an electric motor 24, mounted 85 on a platform on the frame 16, by a round belt 25 that runs over said wheel and a relatively small wheel 26 on the armature shaft of said motor. Both wheels 23 and 26 have grooved peripheries to receive the belt 25. 90

An endless feed belt 27, which also assists the roller 19 in its folding action, runs over said roller 19 and the driven roller 22 and under the front roller 18 for driving the same. The belt 27 is driven by the roller 22 95 in the direction of the arrow marked thereon in Fig. 4 and in turn drives the rollers 18 and 19 in the direction of the arrows marked thereon in the same figure. Said belt 27 is held by the rollers 18-19-22 so that it is upwardly and rearwardly inclined from the roller 22 and the roller 18 holds the upper section of said belt so that it travels substantially parallel to the lower section thereof. The width of the belt 27 is considerably 100 less than that of the rollers 18-19-22 and travels over the intermediate portions thereof. By reference to Figs. 4 and 7 it will be noted that the roller 19 has a peripheral groove 28 in which the belt 27 travels, and 110

which groove is of such depth that the face of said belt is flush with the face of the roller 19.

The upper section of the belt 27, between the rollers 18 and 22, is supported on an inclined deck 20, the front end of which is supported at 30 from the hanger bars 20, and the rear end of which is supported from the side bars of the frame 16 by means of a pair of horizontal arms 31 on the longitudinal edges of said deck. To lessen the friction between the belt 27 and deck 29 there are provided transverse anti-friction rollers 32 journaled in bearing members 33 on the under side of said deck and rotate in longitudinally spaced grooves 34 in the deck 29 with their upper faces arranged for engagement with the back of the belt 27 as it travels on said deck.

20 Co-operating with the roller 18 is a pressure roller 35, having a relatively small diameter, that extends parallel to the roller 18 and rests directly on the top thereof for co-operation therewith for feeding the sheets π edgewise from the table 17. This pressure

25 roller 35 has a shaft 36 journaled in open seats 37 in upstanding bearings 38 on the side members of the frame 16 with freedom to permit said roller 35 to float radially in respect to the roller 18. The roller 19 has its shaft journaled in loose bearings 39 mounted in elongated seats in the side members of the frame 16 and supported on coiled springs 40 that act as tighteners for the belt 27.

Extending parallel with the roller 22 and resting on the belt 27, where it passes over the roller 22, is a creasing roller 41 journaled in the hanger bars 20.

40 A long tongue-like platen or transverse folding plate 42 overlies the upper section of the belt 27 on the deck 29 and extends longitudinally thereof substantially the full distance between the rollers 18 and 22. The 45 upper end of the folding plate 42 is rigidly secured to the under side of a transverse bar 43, the ends of which are rigidly secured to the side bars of the frame 16. This end of the folding plate 42 is spaced slightly 50 above the belt 27 to permit one of the sheets π , when longitudinally folded by the rollers 18 and 19, to pass thereunder on the belt 27. The folding plate 42 is in the form of a flat steel bar that is yieldingly pressed onto the 55 belt 27 by a flat spring 44 that bears longitudinally on the intermediate portion of said plate and has its upper end portion bent upward and anchored to the top of the frame 16. It is highly important to note that the 60 width of the folding plate 42 is slightly tapered from its free end rearward, substantially two-thirds of its full length. For guiding the lower section of the belt 27 there is secured to the deck 29 a pair of depending 65 guide plates 45 between which the belt runs.

A pair of long flat plates 46 are attached to the tops of a pair of parallel rails 47 mounted in rabbeted seats 48 in the top longitudinal edge portions of the deck 29, and each of said rails is detachably secured 70 to said deck by a single upstanding screw stud 49 anchored to said deck and extending through aligned bores in the respective rail and plate 46 and has applied to its other end a thumb nut 50. The rabbeted seats 48 securely hold the parallel rails 47 against angular movement. These plates 46 extend parallel to the deck 29 and their inner longitudinal edge portions extend inward from the rails 47 and afford folding flanges 51 75 spaced above the belt 27. It will be noted by reference to Fig. 12 that the rails 47 are closely positioned to the longitudinal edges of the belt 27 and guide the same. The rear ends of the plates 46 are downwardly and 80 rearwardly inclined to a point below the belt 27 and have cam-acting lifting inner edges 52 that are connected to the adjacent ends of the folding flanges 51 by cam-acting folding edges 53.

Mounted on the forward end portions of the tops of the plates 46 is a pair of flat plates 54 and 55 that overlie the belt 27. These plates 54 and 55 have at their rear ends upwardly curved folding edges 56 and 57, respectively, that extend transversely and obliquely over the belt 27. The folding edge 56 extends inward from the outer longitudinal edge of the respective plate 46 and at an angle of substantially forty-five degrees and terminates substantially midway between the longitudinal edges of the belt 27. The folding edge 57 extends inward from the outer longitudinal edge of the respective plate 46 and at an angle substantially 100 forty-five degrees. Said folding edge 57 is spaced materially forward from the inner end of the folding edge 56 and extends nearly across the belt 27. Forward of the folding edge 57 the plates 54 and 55 extend across 105 the belt 27 and completely cover the same.

For holding a stack of sheets π longitudinally on the table 17 in proper position to be fed by the rollers 18 and 35 to the belt 27 and roller 19, there is mounted on said table a pair of laterally spaced upstanding side plates 58 having on their lower edges outwardly extending flanges 59 that rest directly on said table and are detachably and adjustably secured thereto by thumb screws 60. These thumb screws 60 extend through transverse slots 61 in the flanges 59 and have screw-threaded engagement with the table 17. The slots 61 permit lateral adjustment of the side plates 58 toward or from each other to hold therebetween sheets of different widths. The stack of sheets π on the table 17 between the side plates 58 are fed by hand, one at a time, from the top of the stack edgewise between the rollers 125 120 115 110 105 100 95 90 85 80 75 70 65 60 55 50 45 40 35 30 25 20 15 10 5 0

18 and 35. For the sake of convenience, the edge of the sheet α fed to the rollers 18 and 35 will be hereinafter referred to as the top of the sheet.

During the feeding movement of a sheet α between the rollers 18 and 35 to the rear of the machine the top portion of said sheet is moved onto a flat horizontal bed plate 62 detachably secured to the upper edges of the side members of the frame 16 and the tops of a pair of horizontal cross bars 63 detachably secured to said side members. Formed with the upper edge of the bed plate 62 is a forwardly curved apron 64, the free end of which extends between the rollers 18 and 19. At the longitudinal edges of the apron 64 the bed plate 62 is provided with rail-like extensions 65 secured to the upper edges of the side bars of the frame 16.

20 Mounted over the bed plate 62 is a U-shaped holder 66 having formed with its transverse portion a plurality of edgewise spaced fingers 67 the free ends of which extend obliquely upward. The side members 25 of the holder 66 are downwardly offset to slidably rest on the bed plate 62 and its extension 65 and support the transverse member of said holder and its finger 67 spaced above said bed plate. Rigidly secured to the 30 rear end of the transverse bar of the holder 66 is a depending collar 68 that extends through a longitudinal slot 69 in the bed plate 62 and is slidably mounted on a horizontal guide rod 70, the ends of which are 35 mounted on the holder 66. Obviously, this collar 68 and guide rod 70 secure the holder 66 for straight line sliding movement longitudinally of the machine. The collar 68 is provided with a set screw 71 for securing 40 the same to the rod 70 with the holder 66 set in different positions.

A depending stop flange 72 is formed with the rear edge of the transverse member of the holder 66. On top of one of the 45 fingers 67 is a knob 73 by which the holder may be moved. The position of the stop flange 72, in respect to the rollers 18 and 35, determines the position of a longitudinal fold to be made in a sheet. When a sheet α is to be fed edgewise from the table 17 by the rollers 18 and 35, the same is directed onto the bed plate 62 by the apron 64 and the fingers 67. The movement of the sheet α on the bed plate 62 is limited by the stop flange 72 and when the top of a sheet engages this stop the continued movement of the lower portion of said sheet by the rollers 18 and 35 causes the same to be folded between the rollers 18 and 19 and belt 27 55 and be directed into contact therewith.

Obviously, the apron 64 and finger 67 prevent the sheet α from folding except between the rollers 18 and 19. When the intermediate portion of the sheet α is caught by 60 the rollers 18 and 19 and the belt 27 they

feed said sheets in a reverse direction from that of the rollers 18 and 35. The purpose of mounting the belt 27 in the groove 28 in the roller 19 is to bring the face of the belt 27 flush with the peripheral edge portions 70 of the roller 19 so that said belt and edge portions of said roller contact with the roller 18, and when the sheet α passes between the belt 27—roller 19 and the roller 18, the same is tightly creased thereby throughout 75 its full width. The longitudinally folded edge of the sheet α , in passing from the roller 18 and belt 27, is directed under the folding plate 42. Said sheet α is then carried by the belt 27 under the plate 42 due to the frictional engagement therebetween, and which plate is yieldingly pressed by the spring 44 on said sheet. The width of the folding plate 42 determines the width of the intermediate portion of the sheet α , indicated by 80 broken lines y in Fig. 15, on which lines the sheet α is finally creased. The portions of the longitudinally folded sheet α outward of the folding lines y will hereinafter be referred to as the flaps of said sheet. 85

As the sheet α is moved by the belt 27 longitudinally under the folding plate 42 the flaps of said sheet pass over the oblique ends of the plate 42 and engage the cam edges 52 thereof which lift said flaps and 90 start the folding movement thereof at the longitudinal edges of the folding plate 42. As the sheet α is moved forward by the belt 27 its flaps are further lifted and folded by the cam edges 53 and direct said flaps 100 into contact with the folding flanges 51. During the action of the folding flanges 51 on the flaps of the sheet α said flaps engage the curved folding edges 56 and 57 and, due to the greater angle of the folding edge 105 56 over that of the folding flange 57, the right flap of said sheet is folded under the left flap. These folding edges 56 and 57 fold the flaps substantially flat onto the folding plate 42 so that they are free to pass 110 under the plates 54 and 55 and are held folded thereby. While the folded sheet α is being moved by the belt 27 due to the frictional contact therewith, it is carried under the plates 54 and 55 and withdrawn by 115 said belt from the folding plate 42 and directed under the creasing roll 41 which tightly creases the folded sheet so that it will stay folded. 120

Referring now to the importance of the longitudinal taper of the folding plate 42 (see Fig. 8) I have found that when the flaps of a sheet are folded on parallel lines onto the intermediate portion of the sheet and thereafter subjected to the action of a creasing roll, that during the creasing of the sheet the flaps thereof are forced backward into slight angular relation and hence give the folded sheet a careless and untidy appearance. This difficulty in creasing a fold- 125 130

ed sheet is overcome by folding the flaps of a sheet over the rearwardly converging edges of the folding plate 42 which positions said flaps in angular relation, and in which the front edges of said flaps extend slightly forward of the intermediate portion of the sheet, (see Fig. 8). With the flaps in this position they are fed under the creasing roll and the action thereof forces said flaps rearward so that when the sheet comes from the creasing roll its flaps are accurately folded onto the intermediate portion of the sheet.

It may be here stated that the sheets are only lightly folded over the flaring folding plate 42, so that their flaps will yield and permit movement of the sheet thereover until the projecting front edges of said flaps engage the corresponding roll 41 and be moved backward thereby to position said flaps in parallel arrangement and thus permit the sheet to be freely stripped from said plate under the pulling action of the belt 27 and corresponding roll 41.

For short sheets that do not have to be folded longitudinally the machine is adjusted by removing the bars 63 and the parts carried thereby and mounting a deflecting plate 74 in vertical slots 75 in the sides of the frame 16, as shown in Fig. 6. This deflecting plate 74 is arranged to direct a sheet π from the rollers 18 and 35 between the rollers 18 and 19 and the belt 27. From the rollers 18 and 19 a short sheet is folded transversely in the same manner as that previously described.

From the feed belt 27 and creasing roller 41 the folded sheets are delivered to a trough-like receptacle 76 that extends longitudinally forward of the machine with its front end resting on the same support as that of the machine. The inner end of the receptacle 76 is held raised so that the bottom thereof is inclined, as shown in Fig. 2 by a pair of arms 77 having hook-like ends that are detachably interlocked with apertured lugs 78 on the lower ends of the hanger bars 20. A packer plate 79 is intermediately pivoted to the transverse portion of a bail 80 for swinging movement in a vertical plane. The arms of said bail 80 are detachably pivoted to screw studs 81 on the outer face of the hanger bars 20.

The rollers 18, 19, 22, 35 and 41 and the belt 27 are either of rubber or rubber faced, and during the operation of the machine they are continuously driven without the use of gears or metallic contacting parts, thus rendering the machine noiseless. The attachment 62 and associated parts, and the attachment 74 are selective at will to deflect a sheet fed into the machine and cause the same to be folded when delivered to the belt or to be delivered to the belt without being folded.

The above described paper folding ma-

chine is without time arranged movement and operates continuously, thus eliminating the necessity of careful feeding of sheets, and speeds up the work. The continuously operating machine will function at any part of its movement when a sheet is fed thereto either by hand or automatically from a mimeograph or other machine.

What I claim is:

1. In a paper folding machine, the combination with a pair of co-operating combined feeding and folding rollers, of a pressure roller co-operating with one of said rollers, an endless folding and conveyer belt arranged to run in an intermediate circumferential groove in the other of said rollers and operative to drive the roller with which the pressure roller co-operates, and a stop for a sheet being fed edgewise by the pressure roller and co-operating combined feeding and folding roller, to impart the initial folding movement to the sheet and direct its intermediate portion between the combined feeding and folding rollers. 75

2. In a paper folding machine, the combination with an endless conveyer belt, of a folding plate overlying said belt, the longitudinal edges of said plate being in diverging relation in respect to the direction of travel of the operative section of said belt, sheet folding means co-operating with the folding plate, and means for creasing a sheet folded by said plate and folding means. 95

3. In a paper folding machine, the combination with an endless conveyer belt, of a folding plate overlying said belt, means operative to feed a sheet edgewise between said belt and plate, the longitudinal edges of said plate being in diverging relation in respect to the direction of travel of the operative section of said belt, sheet folding means co-operating with the folding plate, and means for creasing a sheet folded by said plate and folding means. 100

4. In a paper folding machine, the combination with an endless conveyer belt, of a folding plate having an oblique folding edge in respect to the direction of travel of the operative section of said belt, sheet folding means co-operating with the folding plate, and means for creasing a sheet folded by said folding plate and folding means. 115

5. The structure defined in claim 4 in which the folding plate is yieldingly pressed onto said belt. 120

6. The structure defined in claim 4 in further combination with a roller over which said belt runs at its delivery end, and a sheet creasing roller co-operating with said belt as it passes over said roller. 125

7. In a paper folding machine, the combination with an endless conveyer belt, of a deck over which said belt runs, a folding plate yieldingly pressing said belt on the 130

deck, sheet folding means co-operating with said plate, and transverse antifriction rollers working in slots in said deck and engaging the back of said belt.

- 5 8. In a paper folding machine, the combination with a deck, of an endless conveyer belt arranged to run over said deck, a folding plate overlying said belt and deck, a pair of rails mounted on the deck with said plate 10 extending therebetween, and folding flanges mounted on said rails for co-operation with said plate.

9. The structure defined in claim 8 in which said flanges have inclined sections for 15 directing the flaps of a sheet onto said flanges.

10. The structure defined in claim 8 in which said flanges have inclined sections for directing the flaps of a sheet onto said flanges 20 and cam-acting inner edges.

11. The structure defined in claim 8 in which said rails and deck have rabbeted interlocking engagement, and in further combination with a thumb screw for securing 25 each rail to the deck.

12. In a paper folding machine, the com

bination with a frame, of sheet folding means, an endless conveyer belt, and a receptacle at the delivery end of the machine for receiving the folded sheets from said belt, said receptacle having arms detachably supporting the inner end of the receptacle from said frame with the bottom of said receptacle inclined.

13. The structure defined in claim 12 in further combination with a floating packer co-operating with said receptacle.

14. In a paper folding machine, the combination with a pair of combined feeding and folding rollers, of an idle pressure roller co-operating with one of the rollers of said pair, a driven roller, an endless combined feeding and conveying belt arranged to run over said driven roller and one of the rollers of said pair and under the other roller of said pair to drive the same, a folding plate overlying the belt, and sheet-folding means co-operating with said folding plate.

In testimony whereof I affix my signature.

JOHN H. ADAMS.
